FLUSH TANK

Jesse C. Owens, Los Angeles, Calif.

Application February 15, 1943, Serial No. 475,863

6 Claims. (Cl. 4—44)

1

My invention relates generally to the water storage tanks and valves that are used in combination for the flushing of fixtures such as toilet bowls, urinals and the like and the principal objects of my invention are to provide a simple, practical and inexpensive flushing water storage tank and to combine therewith a highly effective flushing valve of the ball cock type which combined parts co-operate to function with high efficiency and without the undesirable hissing and gurgling noises which usually attend flushing operations and the refilling of the bowl and storage tank.

Further objects of my invention are, to provide a combined storage tank and ball cock flush valve that are capable of being readily installed in ordinary storage tanks or combined with and made a part of flushing tanks specifically formed for use in conjunction therewith, and further, to provide the storage tank with a substantially goose-neck-shaped structure having a siphonic duct that is highly effective in "boosting" or inducing the rapid flow of stored water from the tank into the toilet fixture and, further, to provide simple and efficient means for controlling and quieting the flow of water through the gooseneck.

Further objects of my invention are to provide means for producing siphonic action within the gooseneck so as to start and accelerate the flow of water therethrough and to provide simple means associated with the flush valve, for producing a repeat or double flushing action, if desired.

A further object of my invention is to provide a flushing valve and storage tank of the general character indicated that will operate with maximum efficiency with either high or low pressures of water supply.

A still further object of my present invention is to provide means for counteracting and breaking any siphonic conditions which may develop tending to draw contaminated water into the fresh water supply line.

With the foregoing and other objects in view, my invention consists in certain novel features of construction and arrangement of parts that will be hereinafter more fully described and claimed and illustrated in the accompanying drawings in which:

Fig. 1 is a top plan view of a combined storage tank and ball cock flush valve incorporating the principles of the present invention.

Fig. 2 is a vertical section taken on the line 2—2 of Fig. 1.

Fig. 3 is an enlarged vertical section taken on the line 3—3 of Fig. 1, showing the internal structure of the flushing valve.

Fig. 4 is an enlarged fragmentary cross section taken on the line 4—4 of Fig. 1.

2

Fig. 5 is a detail section taken on the line 5—5 of Fig. 2.

Fig. 6 is a sectional view taken on the line 6—6 of Fig. 2.

Fig. 7 is an enlarged sectional view taken on the line 7—7 of Fig. 2.

Fig. 8 is an enlarged cross sectional view taken on the line 8—8 of Fig. 2.

Fig. 9 is a detail view of the adjusting screw for limiting the downward movement of the valve's float.

Fig. 10 is a sectional view showing a modified form of connection between tubular parts of the device and the tank.

Fig. 11 is an enlarged detail view of a part of the ball cock flush valve.

Fig. 12 is a detail section of a modified form of the piston valve used in the ball cock.

Referring by numerals to the accompanying drawings which illustrate a preferred embodiment of my invention, 10 designates a water storage tank which may be formed of wood, porcelain, plastics, composition such as woodstone or the like, and detachably secured to the bottom of the tank is a short externally threaded tube 11, to the lower end of which is connected a duct (not shown) that leads to a toilet bowl or urinal. In the event that the tank 10 is formed of plastics, porcelain or composition as illustrated, the upper portion of the tube 11 may be screwed through a lug 10a formed on the tank bottom. In the case of tanks otherwise formed, the upper end of the tube 11 may be provided with outwardly projecting flanges and secured by means of cement in a recess that is formed in the under surface of the bottom of the tank in a manner similar to that in which the water supply pipe is secured to the tank (see Fig. 10).

A portion of the tube 11 projects above the lug 10a, and detachably connected thereto is a tubular gooseneck 12 comprising an inlet portion 13, an intermediate portion 14 and an outlet portion 15. The inlet portion 13 slopes upwardly at approximately ten or fifteen degrees with respect to the vertical from its open lower end 13a. The intermediate portion 14 slopes downwardly at substantially forty-five degrees from the upper end of the inlet portion 13 and the outlet portion 15 extends laterally from the lower end of the intermediate portion 14 from which it inclines upwardly slightly in establishing communication with the upper end of the discharge tube 11.

A gasket 16 is positioned between the lug 10a and the gooseneck around tube 11 and a cushion 55 17 of rubber or the like, is positioned between the tank bottom and a short leg 12a that extends downward from the gooseneck 12 adjacent the intersection of the intermediate and outlet portions 14 and 15, respectively.

In order to equalize and silence the flow of

water through the tube 11, one or more longitudinally disposed partitions 18 is located in tube 11 and a continuous partition 19 centrally arranged within and extending lengthwise through the upper portion of the inlet portion members 13, the full length of the intermediate portion 14, and nearly the full length of the outlet portion 15, serves the same purpose in the gooseneck 12.

In order to accelerate the boosting effect produced by the gooseneck during flushing operations, particularly where low pressure water supply conditions exist, the gooseneck is provided adjacent the lower end of its intermediate portion 14, with a lateral tubular extension 20 (see Figures 1 and 4) having an opening 21 normally closed by a weighted gravity valve 22 which is connected as by a link or chain 23 to an arm 24 (see Fig. 1) that is carried by a manually actuated shaft 60 of the flush valve, to be hereinafter more fully described (see Fig. 4).

Where the tank is formed of porcelain, plastic or composition, the tank bottom below the open lower end of the gooseneck member 12 is increased in thickness to form a rib 10b which extends upwardly along the inner surface of the tank 10. Formed in the outer portion of this rib adjacent the end wall, is a vertically disposed duct 25, and connected to the lower end is a water supply pipe 26. If desired, this pipe 26 may be provided with external flanges 26a and cemented in a recess in the bottom of the tank, as seen in Fig. 10.

Also formed in the rib 10b are parallel ducts 27 and 29 the upper ends of which both open into a small chamber 10d adjacent the upper end of the rib 10b. The lower end of the duct 27 communicates through an opening 28 with the interior of the discharge tube 11; and the lower end of the duct 29 communicates with a tube 30 which inclines upwardly into the inlet portion 13 of the gooseneck 12.

The length of the tube 30, i. e., the point at which its upper end is located, is determined by the pressure of the water supply in the main, a relatively long tube 30 being employed when the available water supply is at low pressure and a shorter one for high pressures.

Just below the upper edge of the tank 10, the rib 10b terminates in a suitably enlarged portion, or boss, 10c upon which is mounted a float-actuated flushing valve which is indicated at its entirety at 40. This valve 40 is mounted upon the boss 10c by means of a tubular member 32 having threads 32a formed on its outer surface, these threads serving as the means for rigidly mounting the valve 40 in position. An aperture 33 in the tubular member 32 registers with the upper end of the water supply duct 25. A cylindrical flange 34 of materially greater diameter than the tubular member 32 is supported thereon in axial alignment therewith by means of a radially extending flange 34a; and upon the outer end of this cylindrical flange 34, an annular flange 35 is supported, the inner face of this flange 35 being seated against the outer face of the boss 10c while the outer face of the annular flange 35 is spaced outwardly from a valve seat 38 which is formed on the inner end of the tubular member 32, with the result that another annular valve seat 39 is formed on the inner peripheral edge of the annular flange 35 in substantially planar alignment with the valve seat 38, thus providing an annular opening 36 between the valve seats 38 and 39, which opening leads into a substantially annular chamber 37 encircling the inner end of

the tubular member 32. A bell-shaped portion 40a of the housing of the valve 30 is secured to the outer face of the flange 35 as by a plurality of screws 35a and a short horizontally disposed cylinder 41 is carried by the bell-shaped portion 40a. A flexible diaphragm 42 is clamped around its outer peripheral edge between the flange 35 and the base of the bell-shaped member 40a and this diaphragm which is preferably composed of rubber, leather, rubberized fabric, or the like, normally rests on both valve seats 38 and 39, thus normally closing the annular space 36. A disc 43 of relatively thin resilient material bears against the outer face of the diaphragm 42 against which it is retained by a centrally arranged tubular rivet 44. That end of the tubular rivet 44 which is disposed within the bore of the tubular member 32 serves as a seat for a small disc valve 45 which is carried by a valve stem 46, one end of which is rigidly secured to a piston 48 reciprocally mounted within the cylinder 41 and the other end of which extends loosely through the bore of the tubular rivet 44 so as to receive the disc valve 45 thereon in position to engage and effectually close the associated end of the tubular rivet 44 when the piston 48 moves to the right, as viewed on Figure 3. This same stem 46 also carries another disc valve 45a in position to engage the opposite end of the tubular rivet 44 and effectually close it when the piston 48 returns to that position in which it is illustrated in Figure 3. As is best shown in Figure 11, a bleed opening 45b is formed in each of the valve discs 45 and 45a, thus providing for a limited amount of flow through the tubular rivet 44 regardless of which of the valve discs 45 or 45a is in engagement with the rivet 44. Consequently, the bore of the tubular member 32 is always in communication with the interior of the bell-shaped housing member 40a to the extent that equalization of pressures in both these chambers is assured.

When the piston valve 48 moves to the right from the position in which it is illustrated in Figure 3, it draws with it the stem 46, with the result that the valve disc 45 engages the associated end of the tubular rivet 44 and, upon continued movement to the right, withdraws the diaphragm 42 off both valve seats 38 and 39, and when the piston returns to the Figure 3 position the disc 45 so engages the rivet 44 that the diaphragm 42 is returned into sealing engagement with both annular valve seats 38 and 39.

A packing 48a is provided in the inner end of the piston 48 in position to effectually engage a valve seat 49 encircling the opening 47 through which the stem 46 extends into the cylinder 41, thus providing positive assurance against leakage into the cylinder 41 when the piston 48 is in its Figure 3 position.

Preferably a pair of parallel arms 41a extending beyond the inner end of the cylinder 41 support a pintle pin 50 upon which a head 51 is pivotally mounted. The axis of the pintle pin 50 is horizontal and preferably it is disposed slightly below the axis of the cylinder 41 and its piston 48. Aligned conical recesses 52 and 53 are formed in the inner face of the rocking head 51 and the outer face of the piston 41 respectively. The rounded ends of a pin 54 are seated within the two conical recesses 52 and 53, this pin preferably being retained in position, thus interconnecting the rocking head 51 and the piston 48 by pivot pins 55.

A rod 56 rigid with the head 51 extends outwardly therefrom and carries a suitable float 57

at its outer end, and projecting upward from the rocking head 51 is a finger 58, the upper end of which is curved toward the valve 40 as indicated at 59.

A shaft 60 is journaled in suitably aligned bearings 60a which are preferably formed upon the upper side of the cylinder 41 and a short arm 61 rigid with the shaft 60 extends radially therefrom. A notch or recess 62 is formed in the outer end of the arm 61 within which the rounded end 59 of the finger 58 is adapted to seat when the shaft 60 is rotated in counter-clockwise direction as viewed upon Figure 3 through a distance great enough to bring the recess 62 into registry with the rounded end 59.

The shaft 60 extends through a bearing 60b in a wall of the tank 10 and the outer end of the shaft 61 carries a manually operable handle 63. The shaft 61 also carries a preferably adjustably mounted arm 64 carrying a counterweight 65a on its outer end, the parts being so proportioned and arranged that the counterweight 65a, urged by gravity, yieldably retains the shaft 60 in that position wherein the arm 61 is disposed with its notch 62 out of registry with and below the enlarged end 59 of the finger 58, i. e., in its Figure 3 position.

An opening 65 is provided in the lower portion of the annular flange 34 of the valve 40, this opening 65 establishing communication between the annular chamber 37 and the chamber 10d with which the upper ends of both ducts 27 and 29 communicate. An air inlet opening 67 is provided in the rib 10b just below the boss 10c, this opening establishing communication between the interior of the tank 10 and the upper ends of both ducts 27 and 29. The function of this opening 67 is to break any vacuum that might develop within the ducts 27 and 29 should the valve 40 be opened at any time when the supply of water under pressure through the supply pipe 26 is interrupted. This avoids all possibility of the development of syphonic conditions which otherwise might tend to draw contaminated water from the flush tank 10 through the duct 29 or from the toilet fixture through the duct 27 back through the valve 40 and into the water supply system with which the supply pipe 26 communicates, if the supply of water in the pipe 26 is interrupted and a partial vacuum developed therein.

Preferably a bleeder duct 68 leads from the inner end of the cylinder 41 downwardly to establish communication with the chamber 10d so as to provide for disposing of any water that might otherwise collect within the cylinder 41.

Depending from the lower side of the rocking head 51 is a lug 69 through which an adjusting screw 70 is threaded. Another lug 71 formed on the under side of the cylinder 41 in alignment with the lug 69 has an opening 72 therethrough through which an extension 73 of the screw 70 extends with a sufficient degree of looseness to permit free sliding movement of the portion 13 with respect to the lug 71. However, the extent of such movement is limited by a coil spring 75 which is under compression between the lug 72 and a shoulder 74 formed on the screw 70. By adjustment of the screw 70 the degree of compression of the spring 75 can be regulated, thereby making possible variation of the distance through which the rocking head 51 can rotate in response to downward movement of the float 57. In this manner, the degree of opening of the valve 40 can be regulated so as to determine the velocity

with which water is expelled through the tube 30 upwardly into the inlet end 13 of the gooseneck 12.

The float 57 should be so positioned, by bending the rod 56, so that the maximum water level within the tank 10 is approximately as indicated by the dotted line x—x of Figure 2. When the water level within the tank is at this position, the float 57, floating upon the surface of the water, maintains the valve 40 closed by forcing the piston 48 to its Figure 3 position, and, as hereinabove described, causing the diaphragm 42 to seat upon the valve seats 38 and 39, thereby preventing flow of water from the supply pipe 26 beyond that end of the central tubular member 32 of the valve 40 upon which the valve seat 38 is formed. Owing to the presence of the bleeder holes 45b in the disc valve 45a, sufficient water under pressure is permitted to flow past the diaphragm so as to equalize pressures on both sides of the diaphragm and thereby avoid the tendency for the water under pressure within the supply pipe 26 to unseat the diaphragm. However, since the diaphragm also seats upon the valve seat 39, which describes a circle of less diameter than the reinforcing disc 43, distortion of the diaphragm 42 by such fluid pressure acting on the opposite side of the diaphragm from that which bears against the valve seats is prevented.

To operate the hereinabove described apparatus, the handle 63 should be depressed, rotating the shaft 60 in a counter-clockwise direction as viewed in Figure 3. The relationship between the arm 61 on the shaft 60 and the finger 58 with its curved end 59, carried by the rocking head 51, is such that as the shaft is so rotated the arm 61 causes the finger 58 and head 51 to rotate in a clockwise direction as viewed upon Figure 3, throughout a distance sufficient to move the piston 48 to the right far enough to unseat the diaphragm 42 from the seats 38 and 39. This movement of the head 51 also causes the float 57 to move downwards, submerging the float 57 within the water in the tank 10. Unseating the diaphragm 42 from the seat 38 permits water to flow from the supply pipe 26 through the tubular member 32 around the seat 38 and thence through the opening 36 to discharge through the chamber 10d into both ducts 27 and 29. It should be explained that the relationship of the upper ends of the ducts 27 and 29 to the chamber 10d is such that most of the water will be carried from the chamber 10d through the duct 29 and only a relatively small portion delivered by the duct 27 directly to the discharge, or outlet tube 11.

The major portion of the water thus delivered through the valve 40 is forced upwards through the tube 30 and discharges from the upper end thereof as well as through a series of jet openings 31 formed in the side of the tube 30 within the inlet member 13 of the gooseneck 12. The water delivered to the gooseneck 12 is ejected from the tube 30 at considerable velocity, flowing upwards within the member 13 preferably on both sides of the partition 19 in such a manner as to carry a considerable quantity of the water filling the member 13 to the level of the line x—x over the bend of the gooseneck 12, defining the juncture of the portions 13 and 14. The amount of water constituting this quantity will be determined by the adjustment of the screw 70 which limits the extent of opening of the valve 40, as hereinabove described, and should be so regulated as to cause development of the syphonic conditions within the gooseneck 12

which will cause the remainder of the water within the tank 10 to be drawn through the opening 13a in the lower end of the inlet portion 13, through the gooseneck 12, and thence into the outlet tube 11. However, the valve 40 should not be permitted to open to such an extent that after the level of the water within the tank 10 has dropped below the upper end of the discharge tube 30, the water continuing to be ejected from the tube 30 can pass over the bend between the portions 13 and 14, but instead will fall back through the inlet portion 13 and flow through the opening 13a back into the tank 10 so as to cause the tank 10 to be refilled after the flushing action has been completed, it being understood that after the level of the water within the tank 10 has dropped to below the opening 13a, air will be drawn into the gooseneck 12, thereby breaking syphonic conditions therein and causing the flow of water from the tank 10 through the gooseneck 12 to cease. Furthermore, as the tank 10 becomes filled again, the float 57 rises with the water, gradually closing the valve 40, and thereby so reducing the velocity with which water is delivered through the tube 30 that the danger that a sufficient quantity of water again will be carried over the crest of the gooseneck 12 to cause an accidental successive flushing action is avoided.

After the flushing action has been completed, flow of water through the valve 40 will continue owing to the lowered position of the float 57 and the consequent open position of the valve 40. As stated, most of the water flowing from the valve 40 will flow through the duct 29 to refill the tank, while a relatively small amount of the water will flow through the duct 27 into the outlet tube 11 so as to assure the retention of a suitable amount of water within the toilet fixture in accordance with plumbing requirements in many localities.

I claim:

1. In a toilet fixture flushing apparatus, a tank comprising walls and a bottom and having an inlet and an outlet, a float-controlled refill valve mounted for operation within said tank, a gooseneck within said tank having its open inlet end located near the bottom of said tank and its outlet end connected to said tank's outlet, means providing a duct leading from said tank's inlet to said valve, means providing a duct leading from said valve to said inlet end of said gooseneck, a tube communicating with said last mentioned duct and projecting therefrom upwardly into said inlet end of said gooseneck, and a longitudinally disposed partition within said gooseneck extending therein from adjacent the upper end of said tube to a position adjacent said outlet end of said gooseneck.

2. In a toilet fixture flushing apparatus, a tank comprising walls and a bottom and having an inlet and an outlet, a float-controlled refill valve mounted for operation within said tank, a gooseneck within said tank having its open inlet end located near the bottom of the said tank and its outlet end connected to said tank's outlet, means providing a duct leading from said tank's inlet to said valve, means providing a duct leading from said valve to said inlet end of said gooseneck, a tube communicating with said last mentioned duct and projecting therefrom upwardly into said inlet end of said gooseneck, said

tube having a plurality of jet-forming openings therein at different elevations within said inlet end of said gooseneck, and a longitudinally disposed partition within said gooseneck extending therein from adjacent the upper end of said tube to a position adjacent said outlet end of said gooseneck.

3. The combination with a flush tank having an outlet, of a gooseneck within said tank, the inlet end of said gooseneck being disposed above the bottom of said tank and its outlet end being connected to the tank outlet, and means for providing a main jet of water under pressure and a plurality of secondary jets of water at various elevations into said gooseneck above said inlet end thereof.

4. The combination with a flush tank having an outlet, of a gooseneck within said tank, the inlet end of said gooseneck being disposed above the bottom of said tank and its outlet end being connected to the tank outlet, means for providing a main jet of water under pressure and a plurality of secondary jets of water at various elevations into said gooseneck above said inlet end thereof, and a partition within said gooseneck extending from a point adjacent said jet-providing means to a point adjacent said outlet end of said gooseneck.

5. In flushing apparatus of the character described, the combination with a tank, a valve for controlling the supply of water thereto, a float for opening and closing said valve, and manually operable means for simultaneously depressing said float and opening said valve, of a gooseneck within said tank, the inlet end of said gooseneck being open and disposed above the bottom of said tank and the outlet end of said gooseneck being connected to said tank's outlet, means for conducting water from said valve into said gooseneck above said inlet end thereof, means providing an auxiliary inlet into said gooseneck adjacent said outlet end thereof, a removable closure for said auxiliary inlet, and means actuated by said float-depressing and valve-opening means for opening said closure.

6. In flushing apparatus of the character described, the combination with a tank, a valve for controlling the supply of water thereto, a float for opening and closing said valve, and manually operable means for simultaneously depressing said float and opening said valve, of a gooseneck within said tank, the inlet end of said gooseneck being open and disposed above the bottom of said tank and the outlet end of said gooseneck being connected to said tank's outlet, means for conducting water from said valve into said gooseneck above said inlet end thereof, and jetting it toward the crest of said gooseneck with sufficient velocity to carry water entering said gooseneck independently of said conducting means over said crest and thereby initiating syphonic action within said gooseneck, and adjustable means for limiting the extent of opening of said valve and thereby limiting the force with which water is jetted from said conducting means to an extent that when the level of the water stored within said tank is below said jetting means water issuing from said jetting means will flow back into said tank without reaching said crest of said gooseneck.
